struction Finance Corporation, Chicago, Ill., a
corporation of the United States

Application February 28, 1949, Serial No. 78,843

19 Claims. (Cl. 237—9)

1

Our invention relates to steam systems with special reference to steam systems for drying operations and is directed to improvements on the type of steam system set forth in the Harrison et al. Patent 2,366,332 issued January 2, 1945. The present application is a continuation-in-part of the Harrison et al. application 701,252 filed October 4, 1946, and the Tiller & Hunt application 762,628 filed July 22, 1947, both of which are abandoned. These prior disclosures, as far as consistent herewith, are incorporated in the present disclosure by reference.

Other copending applications disclosing the subject matter related hereto are: S. N. 78,604, filed February 26, 1949; S. N. 78,605, filed February 26, 1949; S. N. 78,842, filed February 28, 1949; S. N. 80,802, filed February 28, 1949; and S. N. 777,894, filed October 4, 1947.

The general object of our invention is to achieve greater efficiency in a steam system by heat conservation and better heat transfer and preferably to do so by means of a compact automatic master control that may be manufactured as a self-contained packaged unit for incorporation in existing steam systems.

A steam system of the type here under consideration is characterized by the release of fluid from the return end of the system into a region of substantially lower pressure for the maintenance and regulation of flow velocity in the system. The steam system is what may be termed a "clear channel system" with open communication from the end of the return line back through the steam-using equipment to the steam source (no traps) so that the velocity throughout the system will be responsive to the pressure drop at the end of the return line created by the release of fluid. In this method of operation a small fraction of the total steam survives to the end of the return line and is termed "acceleration" steam because its release accelerates velocity throughout the system.

Two problems arise in this method of operating a steam system: first, to control the release of acceleration steam effectively, and second, to make the release of steam as economical as possible. The acceleration steam must be released in such amount and such manner as to maintain a particular velocity level or range of velocity best suited for the particular steam system and for maximum economy the B. t. u.'s of the released steam must be reclaimed.

In the disclosure of the above mentioned Harrison patent these two problems of control and economy are met by using a thermostatic valve to govern the release of acceleration steam and using make-up water to cool the thermostat ele-

ment of the valve. Control by the make-up water is highly satisfactory because a specific minimum make-up water demand is inherent in every steam system and may therefore serve as a reliable base for velocity regulation. And it is economical to use make-up water to cool the thermostat because the steam released by the thermostatic valve preheats the make-up water. The make-up water carries the reclaimed heat units directly to the boiler to keep them in the steam system.

It is possible to control the flow velocity of a steam system in this way by the inherent demand for make-up water by the system, no matter how small that demand may be. It is easier to establish this kind of control, however, when the make-up water demand of the steam system is of substantial quantity. In a laundry, for example, the make-up water demand is relatively high, say, on the order of 50% of the total boiler feedwater when the wash water for laundry operation is heated by introducing steam and condensate from the system directly into the wash water in an open tank.

When no steam or condensate in any substantial quantity is taken from the system the make-up water demand may be relatively small. In a laundry, for example, if the wash water is heated by steam coils and the condensate from the steam coils is returned to the boiler, the make-up water demand will be small in quantity. In such a situation care is taken to set up a triggering action whereby a small increment of water reaching a thermostat causes the release of a suitably larger quantity of steam. Such triggering action makes it possible to set up and regulate high-velocity flow through a steam system by means of and on the basis of a relatively small demand for make-up water.

As for economy in reclaiming the heat units of the released steam by make-up water there is a limiting factor in the number of B. t. u.'s that can be transferred to a given quantity of water. This limiting factor becomes important when the make-up water demand is small while the required amount of acceleration steam to be released is relatively large.

It is apparent then that while the use of make-up water to cool the thermostat element of a thermostatic valve is practical, no matter how small the make-up water demand of a steam system, nevertheless it would be advantageous in certain situations to have available other means of controlling the release of acceleration steam and reclaiming the B. t. u.'s of the released steam.

A purpose of the present invention is to provide means other than make-up water for cool-

ing action to achieve reliable velocity control combined with economical use of the released steam. The object is to supplement or replace entirely the make-up water for cooling action to create system-wide velocity.

In various practices of the present invention this object may be attained by recycling make-up water, by recycling condensate, by recycling a mixture of make-up water and condensate, and by withdrawing condensate from some point in the system to supplement or replace the make-up water. Other means to the same end apart from cooling action on the thermostat element of the thermostatic valve may be action carried out upstream from the thermostatic valve. One such action may be the continual withdrawal or pumping of condensate from the return line for the creation of velocity in the system. Another such action may be the condensing of acceleration steam upstream from the valve for the creation of flow velocity in the system.

Further objects of the invention relate to flexibility or adaptability in a control unit of the character described. Flexibility is especially important because the unit must be adapted to the specific requirements of widely different steam systems. In this regard another object of the invention is to provide an exceptionally extensive range of adjustability permitting the control unit to be "tuned" or adjusted precisely to the particular requirements of widely different steam systems.

A further object of the invention is to provide means for promoting flow velocity in the steam system by fluid released from the return side of the system without incurring the flash losses that characterize a conventional open steam system. In this regard it is proposed, in effect, to combine the advantages of open and closed steam systems, the advantage of an open steam system being the availability of a large pressure differential for creating flow velocity and the advantage of a closed steam system being the maintenance of condensate under pressure to prevent flash losses.

The above and other objects and advantages of the invention will be apparent in the following description taken with the accompanying drawings.

In the drawings, which are to be considered as merely illustrative:

Fig. 1 is a front elevation of a typical embodiment of the invention as a self-contained master control unit;

Fig. 2 is a diagram of a representative steam system incorporating one form of the new control unit; and

Fig. 3 is a similar diagram illustrating other practices of the invention.

Fig. 1 illustrates how the invention may be embodied in a piece of apparatus that may be manufactured as a self-contained unit for installation in steam plants, usually in the boiler room. This form of the unit includes an upright tank or receiver 10 and a housing or casing 11 associated therewith. The housing may completely enclose the tank or may, as in the present construction, extend forward from the tank to provide an enclosed space for the numerous elements that make up the control combination. The casing may be of sheet metal construction with upper and lower sliding doors 12 that may be opened for access to the interior. The casing includes a panel board 13 on which are various indicating devices that will be described later.

Fig. 1 shows six pipes connected to the master control unit. These six pipes are: a pipe 14 for supplying supplemental cooling water to the unit; a pipe 15 for supplying new water to the unit; a pipe 16 connected to the discharge side of the usual boiler feed pump; a pipe 17 which is the boiler feed line for supplying water to the boiler; the return line 18 of the steam system and, at a lower level, the pipe 20 to the intake side of the boiler feed pump. If desired, an additional vent pipe 21 may be connected to the vent opening of the tank 10.

Fig. 2 shows diagrammatically the principal elements of a steam system including the important parts of the new master control unit. The parts of the unit itself are shown inside a rectangle 22 indicated by a broken line in Fig. 2. Everything inside this rectangle in Fig. 2 is inside the casing 11 of the unit shown in Fig. 1.

In the system shown in Fig. 2, steam from a boiler 23 is supplied through a header 25 to a plurality of equipment heat exchangers or steam using devices 26. Such devices may be, for example, the various machines in a laundry or the drying equipment used in paper manufacture, plastics, etc. Return pipes 27 from the various pieces of equipment connect with the previously mentioned return line 18.

Instead of traps, each of the return lines 27 is provided with a suitable restriction such as a nipple 28 of relatively small diameter. It will be noted that in such an arrangement there will be open communication from the return line 18 back through the various pieces of equipment 26 to the steam supply so that lowering pressure in the return line 18 will cause flow velocity responses in each of the steam using devices.

The return line 18 is terminally connected to the side of a steam separator 31 which preferably, but not necessarily, also serves as a heat exchanger for using the returned condensate to heat new make-up water. The combined heat exchanger and separator 31 is shaped and dimensioned to permit the condensate to separate from the steam and, if desired, suitable baffles 32 may be added to facilitate such separation.

The condensate that is separated from the steam gravitates through a pipe 33 to the intake side of a condensate pump 35 that is included in the working parts of the master control unit. The pump 35 discharges the condensate upward through a pipe 36. Preferably the pump 35 operates continuously.

A valve 37 is provided in the pipe 33 to cut the heat exchanger off from the pump if desired. When the valve 37 is closed all of the condensate and steam that reaches the heat exchanger 31 must flow from the heat exchanger through a pipe 38. The pipe 38 conducts fluid from the return line 18 into the receiver tank 10.

The pipe 38 leads to a two-stage combined heater and mixer 40 which in turn communicates with a spray head 41. Flow through the pipe 38 into the tank 10 is controlled by a thermostatic valve 42 having a thermostat bulb 43 extending into the spray head 41. The thermostat control is such that the valve 42 opens in response to decrease in temperature of the thermostat bulb 43 and closes in response to increasing temperature of the bulb. The critical temperature at which the valve opens and closes may be varied by virtue of an manual adjustment 45 on the thermostat valve 42.

The steam or steam mixed with condensate that flows through the pipe 38 and the valve 42

enters a central upright passage 46 in the two-stage heater 40 and divides, one portion flowing into an upper jet 47 for the first stage heating of new water, and the other portion flowing into a lower jet 48 for the second stage heating. The upper jet 47 is directed into a Venturi throat 50 and the lower jet 48 is directed into a corresponding Venturi throat 51, each jet and throat forming a low pressure space for the introduction of fluid.

New water for the steam system from the previously mentioned supply pipe 15 passes through a float-controlled valve 52 and through a vent condenser 53 to a pipe 55 that enters the two-stage heater 40 in the low pressure space between the first jet 47 and Venturi throat 50. The resulting mixture flows through a lateral connecting passage 56 into the low pressure space between the second jet 48 and second Venturi throat 51, where it is joined by the second portion of hot fluid from the pipe 38. From the two-stage heater the heated water flows into the spray head 41 in heat-exchange relation with the thermostatic bulb 43. The water is not only heated but is also under considerable pressure in the spray head 41 and is discharged downwardly through the spray ports with considerable violence.

Preferably, the tank 10 is maintained slightly above atmospheric pressure, say, 3 or 4 pounds above atmospheric pressure. For this purpose the tank is of closed construction and the vent 21 is provided with both a vent valve 58 and a relief valve 59. The vent valve 58 may be adjusted at a slightly open position to maintain the desired pressure in the tank or 3 or 4 pounds per square inch and the relief valve 59 may be adjusted to pop off at, say, 8 to 10 pounds per square inch.

It is contemplated that the spray capacity of the spray head 41 will be so limited relative to the input of fluid that the pressure in the spray head will rise above the pressure prevailing in the tank 10 when the thermostatic valve 42 is open. Under such conditions, the pressure in the spray head may go substantially above the tank pressure. It is further contemplated that the extent to which pressure will rise in the spray head under given conditions may be varied either by varying the number of spray openings or changing the size of the spray openings.

When the heated water is released in finely divided particles from the spray head 41 into the interior of the tank 10, the water particles are shattered by flashing action and the non-condensable gases are effectively released from the water to escape upwardly through the vent opening 21. The vent condenser 53 not only reclaims heat from the escaping gases but also condenses any vapors that tend to escape with the gases, the recovered condensate dripping to the bottom of the tank.

The tank 10 contains in its lower portion a reserve body 60 of the deaerated make-up water supplied by the above-described spray action. When the level of this body drops, a suitable float 61 opens the previously mentioned valve 52 by suitable mechanical means including an upwardly extending operating rod 62. If the level of the water body 60 rises too high, it overflows through an overflow pipe 63. To prevent the release of pressure through the overflow pipe 63, the overflow pipe is provided with a float valve 64 that is normally closed but opens automatically whenever the water level in the tank rises

unduly. When desired, the whole water content of the tank may be flushed out by opening a drain valve 66. Preferably signal means is provided, as will be later described, to indicate when the float valve 52 is open. For this purpose, a mercury switch 76 is mounted on a rocker arm 77 of the float-controlled mechanism actuated by the float 61. The mercury switch 76 closes whenever the float drops in response to demand for new make-up water.

The deaerated make-up water, usually at above 212° F. by virtue of the pressure existing in the tank 10, is taken from the tank through the previously mentioned pipe 20 to the intake side of the usual boiler feed pump 67 and is discharged by the pump into the previously mentioned pipe 16 that is connected to the control unit at the top. The pipe 16 is connected to the inlet end of a heat-exchange coil 68 shown diagrammatically in the previously mentioned combined heat-exchanger and steam separator 31. The outlet end of this coil 68 is joined to the previously mentioned boiler feed line 17 as indicated in Fig. 2.

Inside the master control unit means may be provided to divert at least some of the discharge from the boiler feed pump 67 directly into the shell of the combined heat exchanger and separator 31. For this purpose, the pipe in the master control unit that connects with the pipe 16 from the boiler feed pump 67 is provided with a branch 103 leading to a spray head 104 inside the separator 31 and two manually adjustable valves 105 and 106 are provided as shown to permit variation in proportioning the flow between the coil 68 and the spray head 104.

The feed water pump 67 may be controlled in a well-known manner by means responsive to changes in the water level in the boiler 23 or in some practices of the invention may be manually adjusted to run continuously at approximately the rate required to keep the boiler level constant. In either event, the float 61 in the master control tank 10 will drop periodically to cause new water to be supplied to the system in accord with the boiler demand. Since the boiler demand for make-up water varies with the heat load on the system, it is apparent that the master control unit is responsive to changes in the heat load on the system.

The previously mentioned pipe 14 is connected to the pipe 55 as shown in Fig. 2 for the purpose of introducing cooling water into the pipe 55 to supplement the make-up water that is introduced by the float valve 52. The pipe 14 may be connected to various sources of cooling water in various practices of the invention.

In the present arrangement the cooling water is condensate supplied by a piece of steam using equipment 112 that operates on low pressure steam. Fig. 2 shows a supply pipe 113 from the steam header 25 to the piece of equipment 112, this supply pipe being provided with a suitable pressure-reducing valve 115. The return pipe 116 from the piece of equipment 112 may be provided with a suitable restriction 117 and is connected to the coil 118 of a heat exchanger 119. The other end of the coil 118 is connected to the pipe 14.

The heat exchanger 119 has an inflow pipe 120 and an outflow pipe 121 to permit any suitable cooling fluid to be circulated for continuously cooling the condensate flowing through the coil 118.

7
Operation

The manner in which the steam system operates and is controlled by the described unit may be understood from the foregoing description.

Steam condenses in each one of the steam chests in the pieces of equipment 26 to give up heat to the material in process, but a portion of the steam flows continuously into the return line 18 through the restrictions 28 because of the open communication through the system. In this method of operation, the flow velocity is substantially higher than the overall or average velocity in a conventional trap system and the small proportion of steam that is continuously passing through the restrictions 28 effectively carries the condensate out of the steam chests along with non-condensable gases. The drop in pressure at the restrictions 28 causes some of the condensate to flash into steam thereby slightly increasing the steam content of the fluid mixture that reaches the combined heat exchanger and separator 31.

The adjustment 45 of the thermostatic valve 42 is high enough to make the valve open in an intermittent manner thereby to cause pulsating flow throughout the system. In a steam system having approximately 100 lbs. per square inch gauge pressure in the steam header 25 the setting of the thermostatic valve may be, for example, somewhat above 230° F. In any event the temperature setting of the thermostatic valve will be above the normal temperature prevailing inside the tank 10. If the tank 10 is at 4 to 6 lbs. gauge pressure the temperature therein will be in the range 224°-230° F.

Since the temperature in the master control tank is below the temperature setting of the thermostatic valve the environment of the spray header 41 tends to cool the thermostat bulb below the temperature setting thereby to cause the thermostatic valve 42 to open. When the valve 42 opens, however, the thermostat bulb is again heated above its critical temperature by the fluid released from the separator 31 thereby causing the thermostatic valve to close.

Since a temperature above 230° F. cannot be attained in the spray head 41 as long as the spray head interior is at the same pressure as the interior of the tank 10 the initial flow of steam from the thermostatic valve or the initial flash of steam by flash action from condensate released through the valve does not have a temperature above 230° F. Since the restrictive action of the spray openings is effective to cause rising back pressure in the spray header, however, the temperature rises correspondingly and soon climbs above the temperature setting of the thermostatic valve. It is apparent then that the flow passage from the thermostatic valve 42 to the discharge openings of the spray header 41 functions as a pressure accumulation space to make possible the relatively high temperature required for the purpose of valve control as well as for the purpose of deaerating the make-up water.

By virtue of the described cycle of alternate heating and cooling, the valve 42 opens intermittently in an automatic manner to maintain a desired minimum average flow velocity in the system during periods when no new make-up water is flowing. Whenever new make-up water is required, and the float 61 lowers to open the water valve 52, the thermostat bulb 43 is

immediately cooled below its critical temperature. In the usual method of operation, the flow of new water is adequate to keep the thermostatic valve 42 open in opposition to the heating effect of the fluid released by the valve, so that the thermostatic valve stays open as long as the flow of new water continues.

The valve 42 may completely close or only nearly close in response to rising temperature, and the valve may be either a quick-acting valve or a slow-acting valve. If a slow-acting valve is used, it will tend to stay open at an equilibrium position in the absence of water flow and will merely open wider in response to new water. In such instances, the pulsations in the system are governed primarily by the periods of water flow. Since every steam system has losses, however, which must be made up by new water, the new water demand can be relied upon to continually cause opening action of the valve 42 to create pulsations.

Since the master control responds to demand for new water at the boiler end of the system and in doing so speeds up velocity at the return end of the system, the unit may be said to tie the two ends of the system together functionally. The result is a closed chain of causes in which the demand of the boiler for a pound of water to replace a pound of steam consumed in the system causes enough velocity to be created to sweep out the resulting condensate from the steam chests in the system.

When the load on the steam system is steady the master control unit functions as automatic means to keep the overall or average velocity of the pulsating flow at a substantially constant level. Under constant operating conditions, with the average velocity level of the pulsating flow substantially constant, the boiler demand for new water will be met by a substantially constant ratio of new water to condensate. Under such circumstances if velocity were to tend to lag, there would be an immediate deficit in condensate returned and the demand for make-up water would temporarily increase. Such increase in the demand for make-up water would, however, act on the thermostat bulb 42 to increase velocity. Thus, any tendency for velocity to drop would be automatically corrected. In like manner any tendency for velocity to speed up excessively, would be automatically corrected by reducing the demand for make-up water and thereby reducing the quantity of fluid released by the valve 42.

Since changes in the load on the steam system cause corresponding changes in the demand for new water by the boiler with corresponding changes in the quantity of make-up water required in a unit of time, it is apparent that the average or overall velocity of the system also shifts up and down automatically with changes in the load on the system.

Each time the valve 42 opens, it causes two things to happen. It causes a pressure pulsation or slight pressure drop in every steam chest in the system, and it causes velocity in the whole system to speed up. In other words, each opening movement of the valve 42 causes a pressure pulsation in each piece of equipment and at the same time causes a strong surge of flow from the equipment through the return line of the system. The pressure pulsations attack the non-condensable gas films in the steam chests by causing a flashing action because each time the pressure drops slightly, a portion of every par-

ticle of water in the steam chests flashes into steam. There are countless water particles in and near the gas films and at 100 lbs. pressure per square inch the condensate that flashes into steam increases in volume over 240 times. As a result, each particle of water becomes an explosive center of turbulence to disrupt the gas films and to promote heat transfer to the material in process. The gases torn away from the gas films are quickly picked up by the velocity surges and swept into and through the return line of the system. The velocity surges also sweep condensate out of the steam chests continuously and keep the condensate films exceedingly thin.

Only high temperature water reaches the boiler 23 because the condensate that is returned directly to the boiler through the pump 35 is not permitted to drop to atmospheric pressure and because all new water added to the system is effectively preheated. In a system using steam at 100 lbs. per square inch, the condensate passed through the pump 35 is maintained well above 300° F.

The new water is heated in four stages and then is intermixed with the high temperature condensate in the boiler feed line 17. The first stage of heating the new water is in the vent condenser 53; the next two stages are in the two-stage heater 40; and the fourth stage is accomplished by the coils 68 in the combined heat exchanger and separator 31. As a result, the temperature of the make-up water as it leaves the coils 68 is nearly 300°.

The supplemental cooling water introduced through the pipe 14 flows into the pipe 15 in the same manner as make-up water and has the same valve-opening effect on the thermostatic valve 42. In a system having a relatively low demand for make-up water this additional cooling water not only simplifies the problem of causing the thermostatic valve to open for creating adequate flow velocity throughout the system but also solves the problem of reclaiming the heat units of the released acceleration steam. The fact that the pressure in the steam using equipment 112 is relatively low by virtue of the pressure reducing valve 115 would ordinarily insure sufficiently low temperature in the return line 116 for the desired cooling action on the thermostat bulb 43. So in many instances the heat exchanger 119 is not necessary to insure sufficiently cool water supply through the pipe 14.

It is apparent that the arrangement shown in Fig. 2 supplements the velocity-creating effect of the make-up water in several ways. In the first place, the relatively cool water or condensate supplied through the pipe 14 supplements the cooling effect of the make-up water on the thermostat 43. In the second place, because the tank 10 is under pressure, the cooling effect of the vent condenser 53 reduces the pressure and temperature inside the tank with consequent cooling action on the thermostat 43. In the third place, the continuous removal of condensate by the pump 35 from the lower end of the separator 31 creates flow in the return line 18. In the fourth place, the condensing of steam in the separator 31 by the cooling effect of the water coil 68 and/or the cooling effect of water introduced by the spray head 104 serve to promote flow by contraction of the fluid mixture at the end of the return line.

All of these factors working together create and maintain whatever flow velocity is desired in any

particular steam system, independently of the make-up water demand of the system and regardless of how small the make-up water demand may be. This arrangement, moreover, causes all heat units of the acceleration steam to be reclaimed and makes it unnecessary for acceleration steam to be wasted.

In various practices of the invention with the described apparatus, various parts may be taken out of operation if desired. Thus, as already noted, the condensate pump 35 may be cut off so that all the fluid from the return line 18 passes through the thermostatic valve 42 into the tank 10. To change over to this mode of operation it is necessary merely to close the valve 37 to cut off the condensate pump 35 and to raise the temperature settings of the thermostatic valve 42. When the master control unit is operated in this manner, it does not return condensate directly to the boiler under pressure but it does recirculate all of the condensate through the deaeration process to eliminate any air that may be picked up by the condensate.

It is obvious also that circulating pump 130 may be kept out of operation in those instances in which the cooling effect of the make-up water alone on the thermostat 43 is sufficient to keep the system operating at high efficiency.

The instrument panel

In the preferred form of the invention, the panel board 13 is provided with the following instrumentalities. A dial 87 indicates the deaeration temperature, and a dial 88 indicates the deaeration pressure, both values being taken near the thermostatic bulb 43 where the fluid under pressure flows into the spray head 41. A dial 89 shows the return line pressure near the point at which the return line 18 connects with the combined heat exchanger and separator 31. A dial 90 shows the temperature of the feedwater delivered to the boiler through the feed line 17, and a dial 91 shows the pressure of the make-up water supply taken near the connection of the water supply pipe 15 with the unit. A dial 92 indicates the pressure prevailing inside the master control tank 10. A signal lamp 95 is responsive to the mercury switch 76 to indicate the periods in which the system is taking in new water, and a second signal lamp 96 responds to energization of the solenoid valve 70 to indicate the occurrence of water pulses into the two-stage heater 40.

Tuning the unit to suit a particular steam system

A feature of the invention is that it incorporates a number of elements that may be changed or adjusted to cause the master control unit to match precisely the requirements of any steam system within a very wide range. As a result, the control unit is extremely flexible and is not only readily adaptable to the requirements of any particular system but is also adaptable to changes in a steam system such as the addition of new heating equipment.

Any of the following adjustments may be made to vary the operation and control characteristics of the unit:

1. The temperature adjustment 45 of the thermostatic valve 42 may be varied.
2. The rate of supply of the new water may be varied to change the cooling effect of the new water on the bulb 43. For example, the float valve 52 may be restricted or limited in its opening action to any degree desired.

11

3. The closing action of the thermostatic valve 42 as well as the opening action may be limited to any degree desired.

4. The discharge capacity of the spray head 41 may be varied to vary the manner and degree of pressure rise in the spray head.

5. The prevailing pressure in the master control tank 10 may be raised or lowered.

6. The proportion of make-up water diverted to the spray head 104 in the separator 31 may be varied by manipulation of the valves 105 and 106.

7. The cooling action of the heat exchanger 119 on the condensate in the pipe 14 may be varied.

Description of Fig. 3

The arrangement illustrated in Fig. 3 is largely similar to the previously described arrangement Fig. 2 as indicated by the use of corresponding numerals to indicate corresponding parts.

The pipe 14 in the master control unit is shown connected to the coil 118 of the heat exchanger 119 as heretofore described. In this instance, however, the coil receives condensate from a trap 122 of a steam coil 123 that heats water in a closed pressure tank 124. This tank, for example, may be the tank for heating wash water in a laundry. Steam is supplied to the steam coil 123 by a pipe 125 from the steam header 25 and the flow of steam into the coil is governed by a thermostatic valve 126 in a well-known manner.

Fig. 3 shows a water pipe 127 for supplying the tank 124 and shows how the proportion of the new water that is by-passed through the heat exchanger 119 may be varied to vary the cooling effect on the condensate in the coil 118. The by-passed water is preheated by the condensate in the coil 118 and on the other hand, the condensate is cooled down sufficiently to activate the thermostatic valve 42 of the master control unit when the condensate reaches the thermostat 43. The proportion of water by-passed through the heat exchanger 119 is varied by manipulating two valves 128 and 129.

Fig. 3 also includes means for recycling the de-aerated make-up water or more accurately stated, the mixture of deaerated make-up water and condensate stored in the tank 10. This water is recirculated into contact with the thermostat 43 to supplement the valve-operating function of the new make-up water.

Fig. 3 shows a small circulating pump 130 having its intake 131 connected to the tank 10 to draw water therefrom. The output from the pump is delivered through a pipe 132 to the previously mentioned pipe 55 so that it may reach the thermostat 43 to cause opening action of the thermostatic valve 42. A check valve 133 prevents backflow. Preferably a by-pass 134 having a by-pass valve 135 is provided from the discharge side of the pump back to the tank 10. This valve 135 and a second valve 136 in the pipe 132 may be manipulated to vary the amount of recirculated fluid that reaches the pipe 55.

In some instances it is desirable to cool the discharge from the circulating pump 130 for greater cooling effect on the thermostat 43. For this purpose, Fig. 3 shows the discharge from the circulating pump 130 as passing through the coil 137 of a heat exchanger 138. The heat exchanger 138 is provided with an intake pipe 139 and an outflow pipe 140 so that any suitable fluid cooling medium may be circulated therethrough.

12

In the operation of the arrangement shown in Fig. 3, cooling fluid to supplement the cooling effect of the usual make-up water may flow through either pipe 14 or pipe 132 or through both pipes simultaneously. The amount of water flowing through either of the two heat exchangers 119 and 138 may be varied along with other previously mentioned factors in the procedure of "tuning" the unit to the needs and characteristics of any particular steam system.

In the described embodiments of the invention, the separator 31 is to be considered as part of the corresponding return line 18 for the purpose of claiming the invention.

Our description in detail of preferred practices of the invention, for the purposes of disclosure and to illustrate the principles involved, will suggest to those skilled in the art various changes and substitutions under our basic concepts. We reserve the right to all such departures from our disclosure that fall within the scope of our appended claims.

We claim as our invention:

1. In a steam system having a boiler, at least one steam-using device, and a return line, said device and return line forming a clear channel from said boiler for flow-promoting pressure communication through the system, the combination therewith of: a valve to release fluid from said return line to promote flow in said device, a thermostat operatively connected with said valve for closing action of the valve in response to temperature above its setting and opening action of the valve in response to temperature below its setting, said thermostat being positioned to be heated by the discharge from said valve, and means to cool said thermostat with fluid to favor opening of the valve for promoting flow, said cooling fluid being, at least in part, condensate returned from the system.

2. In a steam system having a boiler, at least one steam-using device connected to the boiler, and a return line connecting the steam-using device to the boiler and closed to the outer atmosphere, said device and return line forming a clear channel from said boiler for flow-promoting pressure communication through the system, the combination therewith of: a valve to release fluid from said return line to promote flow in said device, boiler feed means having its intake connected directly with said return line to further promote flow through said device, a thermostat operatively connected with said valve for closing action of the valve in response to temperature above its setting and opening action of the valve in response to temperature below its setting, said thermostat being positioned to be heated by the discharge from said valve, and means to cool said thermostat with fluid to favor opening of the valve for promoting flow.

3. In a steam system having a boiler, at least one steam-using device, and a return line, said device and return line forming a clear channel from said boiler for flow-promoting pressure communication through the system, the combination therewith of: a valve to release fluid from said return line to promote flow in said device, boiler feed means to convey condensate under pressure direct from said return line, a thermostat operatively connected with said valve for closing action of the valve in response to temperature above its setting and opening action of the valve in response to temperature below its setting, said thermostat being positioned to be heated by the discharge from said valve, and

means to cool said thermostat with condensate returned from the system to favor opening of said valve for promoting flow.

4. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of said valve in response to temperature below a given temperature and closing operation of the valve in response to temperature above said given temperature, said thermostat being positioned to be heated by the fluid discharge of the valve, means to direct make-up water into cooling relation with said thermostat for opening action of said valve in response to the demand of the system for water, and means to cool said thermostat additionally with condensate from the system.

5. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, means confining and retarding the discharge from said valve to cause pressure rise therein when the valve is open, a thermostat for causing opening operation of said valve in response to temperature below a given temperature and closing operation of the valve in response to temperature above said given temperature, said thermostat being positioned in said confining means to be heated by the fluid discharge of the valve, means to introduce make-up water into said confining means for cooling of said thermostat in response to the make-up water demand of the system, and means to introduce additional water from the system into said confining means for cooling of the thermostat.

6. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of said valve in response to temperature below a given temperature and closing operation of the valve in response to temperature above said given temperature, said thermostat being positioned to be heated by the fluid discharge of the valve, and means to recycle said fluid discharge at lower temperature into heat-exchange relation with said thermostat for cooling of the thermostat to cause opening action of said valve.

7. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of said valve in response to temperature below a given temperature and closing operation of the valve in response to temperature above said given temperature, said thermostat being positioned to be heated by the fluid dis-

charge of the valve, means to add relatively cool water to the discharge from said valve for cooling action on said thermostat, and means to recycle the fluid discharged by the valve together with the added fluid into heat-exchange relation with said thermostat.

8. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of the valve in response to temperature below a given temperature and closing operation of the valve in response to temperature above said given temperature, said thermostat being positioned to be heated by the fluid discharged from the valve, means to convey condensate from one of said steam-using devices into heat-exchange relation with said thermostat for cooling the thermostat, and a heat exchanger to cool said condensate before the condensate reaches said thermostat.

9. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure for promoting flow in the steam system, means to bring cooling fluid into heat-exchange relation with the contents of said return line for causing condensation of steam therein for further promotion of flow in the steam system, a thermostat for causing opening operation of the valve in response to temperature below a given temperature and closing operation of the valve in response to temperature above said given temperature, said thermostat being positioned to be heated by the fluid discharged from the valve, and means to cool said thermostat with water to increase the opening action of said valve.

10. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of said valve in response to temperature below a given temperature and closing operation of the valve in response to temperature above said given temperature, said thermostat being positioned to be heated by the fluid discharge of the valve, a means to direct make-up water into heat-exchange relation with said thermostat to cause opening action of said valve, and means to discharge make-up water into said return line for flow-promoting condensing action in the return line.

11. In a steam system having a boiler, at least one steam-using device, and a return line, said device and return line forming a clear channel from said boiler for flow-promoting pressure communication through the system, the combination therewith of: a valve to release fluid from said return line into a region of substantially lower pressure, a thermostat for causing opening operation of said valve in response to temperature below a given temperature and closing operation of the valve in response to temperature

15

above said given temperature, said thermostat being positioned to be heated by the fluid discharge of the valve, a means to direct make-up water into heat-exchange relation with said thermostat to cause opening action of said valve, a heat exchanger included in said return line, said heat exchanger having a passage for heating water, and means to direct make-up water into heat-exchange relation with said bulb for cooling action on the bulb and subsequently to direct the make-up water through said passage for flow-promoting condensation in said return line.

12. In a steam system having a boiler, at least one steam-using device, and a return line, said device and return line forming a clear channel from said boiler for flow-promoting pressure communication through the system, the combination therewith of: a heat exchanger included in said return line, said heat exchanger having a passage for heating water, a receiver tank maintained above atmospheric pressure but substantially below the pressure in said return line, a valve to release fluid from said return line into said receiver, a thermostat for causing opening operation of said valve in response to temperature below a given temperature and closing operation of the valve in response to temperature above said given temperature, said thermostat being positioned to be heated by the fluid discharge from said valve, a condenser in said tank, and means to cause make-up water to flow first through said condenser then into heat-exchange relation with said thermostat and then through said passage for flow-promoting condensing action in said return line.

13. In a steam system, a combination as set forth in claim 12, which includes means to cool said thermostat with condensate from the system.

14. In a steam system having a boiler, at least one steam-using device, and a return line, said device and return line forming a clear channel from said boiler for flow-promoting pressure communication through the system, the combination therewith of: a separator included in said return line, a receiver tank maintained above atmospheric pressure but substantially below the pressure in said return line, a valve to release fluid from said return line into said receiver, a thermostat for causing opening operation of said valve in response to temperature below a given temperature and closing operation of the valve in response to temperature above said given temperature, said thermostat being positioned to be heated by the fluid discharge from said valve, a condenser in said tank, means to direct make-up water first through said condenser and then in heat-exchange relation with said thermostat for cooling of the thermostat and then to cool the interior of said separator for flow-promoting condensation from said separator.

15. In a steam system having a boiler, at least one steam-using device, and a return line, said device and return line forming a clear channel from said boiler for flow-promoting pressure communication through the system, the combination therewith of: means to bring cooling fluid into heat-exchange relation with the contents of said return line for causing condensation of steam therein to set up a pressure differential across the system for promotion of flow in the system, a condensate pump for returning condensate to said boiler, said condensate pump having its in-

16

take port in a communication with said return line to remove condensate therefrom for further promotion of flow in the system, a valve to release fluid from said return line into a region of substantially lower pressure than the return line to set up a still further pressure differential across the system for still further promotion of flow in the steam system, a thermostat controlling said valve, said thermostat being positioned for rise in temperature by heat supplied by said return line, and means to cool said thermostat with fluid to modify the operation of said valve, said fluid being, at least in part, condensate from the system.

16. In a steam system having a boiler, at least one steam-using device and a return line, said device and return line forming a clear channel from said boiler for flow-promoting pressure communication through the system, the combination therewith of: means to release steam from said return line thereby to promote flow through the system, means to provide condensate from the system apart from said return line at a temperature substantially lower than the temperature in said return line, means to bring said released steam into heat-exchange relation with said condensate, thereby to condense at least a part of said steam and at the same time to raise the temperature of the condensate, and means to return said heated condensate to said boiler under sustained pressure.

17. In a steam system, a combination as set forth in claim 16, in which said means for bringing steam into heat-exchange relation with condensate intermixes the steam and condensate.

18. In a steam system having a boiler, at least one steam-using device and a return line, said device and return line forming a clear channel from said boiler for flow-promoting pressure communication through the system, the combination therewith of: means to provide condensate from the system apart from said return line, means to cool said condensate substantially below the temperature prevailing in said return line, means to release steam from said return line into heat-exchange relation with said condensate, thereby to raise the temperature of the condensate and at the same time to condense at least a part of said released steam.

19. In a steam system having a boiler, at least one steam-using device and a return line, said device and return line forming a clear channel from said boiler for flow-promoting pressure communication through the system, the combination therewith of: means to provide condensate from the system apart from said return line, means to cool said condensate substantially below the temperature prevailing in said return line, and means to bring said condensate into heat-exchange relation with steam that reaches the end of the system through said return line, thereby heating the condensate and at the same time condensing said steam.
